US0D1107583S

(12) United States Design Patent (10) Patent No.: US D1,107,583 S
(45) Date of Patent: * Dec. 30, 2025

(54) ARTICLE OF JEWELRY

(71) Applicant: LOUIS VUITTON MALLETIER,
Paris (FR)

(72) Inventors: Francesca Amfitheatrof, Paris (FR);
Dominique Tissier, Paris (FR)

(73) Assignee: Louis Vuitton Malletier, Paris (FR)

() Term: 15 Years

(21) Appl. No.: 29/859,451

(22) Filed: Nov. 10, 2022

(30) Foreign Application Priority Data

May 19, 2022 (FR) 20222238

(57) CLAIM

The ornamental design for an article of jewelry as shown and described.

DESCRIPTION

FIG. 1 is a perspective view of an article of jewelry showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is another perspective view of the article of jewelry as shown on a necklace.

The broken lines illustrate environmental structure matter and form no part of the claimed design.

1 Claim, 8 Drawing Sheets
